(57) **CLAIM**

The ornamental design for a coupling for pipes and hosing, as shown.

DESCRIPTION

FIG. 1 is a perspective view of a coupling for pipes and hosing embodying my design.

FIG. 2 is a side elevational view thereof.

FIG. 3 is a plan view thereof; and,

FIG. 4 is an end elevational view thereof.

The broken line showing is included for the purpose of illustrating environment and forms no part of the claimed design.
